(57) **CLAIM**

The ornamental design for a rear bumper part for vehicle, as shown and described.

DESCRIPTION

FIG. 1 is a perspective view of a rear bumper part for vehicle showing my new design;

FIG. 2 is a rear view thereof;

FIG. 3 is a front view thereof;

FIG. 4 is a right view thereof;

FIG. 5 is a left view thereof;

FIG. 6 is a top view thereof shown rotated by a slight degree; and,

FIG. 7 is a bottom view thereof shown rotated by a slight degree.

The broken lines in the drawings illustrate portions of the rear bumper part for vehicle that form no part of the claimed design.
